(57) **CLAIM**

We claim the ornamental design for a case for a computing device, as shown and described.

DESCRIPTION

FIG. 1 is an upper perspective view of the case for a computing device;

FIG. 2 is a lower perspective view of the case for a computing device shown in FIG. 1;

FIG. 3 is a bottom plan view of the case for a computing device shown in FIG. 1;

FIG. 4 is a top plan view of the case for a computing device shown in FIG. 1;

FIG. 5 is a left side view of the case for a computing device shown in FIG. 1;

FIG. 6 is a right side view of the case for a computing device shown in FIG. 1;

FIG. 7 is a front side view of the case for a computing device shown in FIG. 1; and,

FIG. 8 is a rear side view of the case for a computing device shown in FIG. 1.

The broken lines in the drawings depict environmental subject matter/or parts of the case for computing device only and form no part of the claimed design. The dot-dash-dot lines represent a boundary of the claim.
